United States Patent Office

Des. 218,863

Patented Sept. 29, 1970

218,863

CARBURETOR

Robert L. Van Camp and Bernard C. Phillips, Toledo, Ohio, assignors, by mesne assignments, to Borg-Warner Corporation, Chicago, Ill., a corporation of Delaware

Filed July 5, 1968, Ser. No. 12,628

Term of patent 14 years

Int. Cl. D15—01

U.S. Cl. D77—1

Fig. 1

Fig. 4

Fig. 2

Fig. 3

Fig. 5

FIG. 1 is a side elevational view of the carburetor embodying my new design;

FIG. 2 is a top plan view of the carburetor shown in FIG. 1;

FIG. 3 is a side elevational view of the opposite side of the carburetor illustrated in FIG. 1;

FIG. 4 is a view of one end of the carburetor, and

FIG. 5 is a view of the other end of the carburetor.

We claim:

The ornamental design for a carburetor, as shown and described.
